FIG. 19.

Brown, Wheeler & Woolard
ATTORNEYS

UNITED STATES PATENT OFFICE.

REUBEN STANLEY SMITH, OF MILWAUKEE, WISCONSIN, ASSIGNOR TO A. O. SMITH CORPORATION, OF MILWAUKEE, WISCONSIN, A CORPORATION OF NEW YORK.

PROCESS OF FORMING CURVED FLANGED BARS.

Application filed March 31, 1920. Serial No. 370,136.

To all whom it may concern:

Be it known that I, REUBEN STANLEY SMITH, a citizen of the United States, residing in the city of Milwaukee, county of Milwaukee, and State of Wisconsin, have invented certain new and useful Improvements in Processes of Forming Curved Flanged Bars (Case No. 149); and I do hereby declare the following to be a full, clear, and exact description thereof, such as will enable persons skilled in the art to which the invention relates to reduce the invention to practice, reference being had to the drawing hereto attached for disclosure as to certain details constituting the dominant features of my invention.

My invention relates to improvements in processes for shaping sheet metal blanks, particular reference being made to that class of structures in which the side margins of a curved sheet metal blank are bent perpendicularly to the central portion or web of the blank to form a channel bar, for example, such as constitutes one of the side bars or cross bars of automobile or other vehicle frames.

My invention is embodied in the process of imparting a succession of edgewise bends to a single rectangular metal plate, so that by distorting the parallel edge lines of such plate, a plate of varying outline will be produced and of such area as to permit a curved blank of predetermined contour to be punched therefrom, it being understood that the maximum width of such curved blank between the projected edge lines thereof greatly exceeds the width of the plate from which the blank is to be punched.

My invention resides also in the process of distorting the cross section of the blank at points so as to increase the thickness thereof, and thus constitute reinforcements in certain areas, and by this procedure I obviate the necessity for separately reinforcing the side bar at the points which are subjected to breaking strains.

Heretofore the general practice has been to punch the curved side and cross bar blanks from rectangular plates or sheets of

metal. This process of thus forming the blanks is wasteful, inasmuch as a rectangular plate of metal having an excess of area has been required to enable a blank of irregular form to be punched therefrom. 55

The practice of imparting an edgewise bend to a sheet metal plate possessing considerable width, so as to distort the superficial area of such plate and conform it to the irregular area of the curved blank, 60 has been productive of a great saving of material, and has greatly reduced the amount of scrap when compared with the scrap created by the older processes of punching the curved blank from a rectangular plate 65 of ample width. In the later process in which the curved blank is punched from a metal plate which has been bent edgewise or in the direction of its width, the side lines of the curved plate are made to conform as closely as possible to the contour 70 lines of the curved blank to be punched therefrom. The skeleton of the curved plate created by punching out the curved blank, is so attenuated that waste is practically 75 eliminated, and the small amount of material remaining in the skeleton has no value other than that of scrap.

While it has been entirely practicable to impart a single edgewise bend or curve to 80 a plural number of plates in one operation, it has not been, prior to my invention, practicable to impart in one operation more than a single bend to such plural number of plates. Nor has it been possible heretofore 85 to bend a single plate edgewise.

The edgewise bending of a plural number of plates in one operation has been achieved by the use of a die member having a thickness equal to the aggregate thickness of the plural number of plates, usually four or five, operated upon at one time. The die so used, by reason of its thickness, possesses a degree of stiffness and rigidity sufficient to cause it to stand up under the great pressure 90 imposed upon it in the bending operation. But the insurmountable obstacle encountered in attempting to bend a single plate edgewise, resides in the inability to construct the thin blade of the die, the thickness of 95 100

which approximates the gauge of the plate to be bent, so as to possess sufficient strength to enable such die to withstand the enormous compressive strain exerted in the bending operation.

But my improved process enables me to impart an edgewise bend to a single plate, and this result is brought about by the use of offsetting dies of improved formation, as will be described hereinafter. In the old practice of offsetting a plural number of plates edgewise, it has been possible to impart but a single bend to such plates in one operation. When other curves were desired in the metal plates it was necessary to subject the plates to further treatment by the offsetting dies in further similar operations.

My improved process contemplates the bending of a single metal plate and imparting thereto in a single operation of the offsetting press, all of the curves, either single or compound, which it may be desired to produce in the curved plate to enable any desired configuration of curved blank to be punched therefrom.

An offsetting press which may be used to carry out the process involving my present invention is disclosed in Patent No. 1,340,138, granted May 11, 1920, on an application filed by Henry Miller, March 30, 1918, Serial #225,791, and also, by the improved offsetting press disclosed in the application filed by R. Stanley Smith, the present inventor, together with Henry Miller and Frederick Orton, March 22, 1920, Serial #367,799. The offsetting presses disclosed in the aforesaid patent and application are designed to operate upon a single metal plate, so as to produce therein by one operation of the press all of the desired curves, and the plate will be so contoured as to enable the particular curved blank to be punched therefrom.

An offsetting press operating in the manner just referred to, will constitute an element of the assemblage of machines disclosed in Patent No. 1,397,020, granted November 15, 1921, on my application, Serial #212,934, filed January 21, 1918, such assemblage including machines, which by their related, connected and successive operations, punch from metal plates the side and cross bar and other blanks used in constructing an automobile or other vehicle frame, shape such blanks according to the particular requirements appertaining to each of them, perform the necessary milling operations thereon, assemble the several constituent frame parts, and secure all of such parts in their respective positions, so that in a continuous operation of mechanical devices a completed automobile or other vehicle frame is automatically produced. The assemblage disclosed in my said Patent No.

1,397,020 is timed to operate upon a schedule providing for the production of a given number of automobile frames per minute, and each machine element of the assemblage performs its operation in a predetermined fraction of the time-cycle of the operation of the assemblage. The requirements imposed by the described co-ordinated operation of the machines of the said assemblage have necessitated the movement of the metal plates in a continuous and uninterrupted stream through the offsetting elements of the assemblage in single file order, and this requirement has been met by the present invention, and the offsetting presses which have been designed to fulfil the purposes thereof. But in actual practice, my present invention as well as the offsetting press, need not be limited to operation upon a single plate, inasmuch as a plural number of rectangular plates may be fed to the offsetting press for bending in a single operation of the press, if such plates are not to be distorted otherwise than in the direction of their width.

As above indicated, it has not been possible heretofore to offset edgewise a single metal plate of considerable width, by reason of the fact that the offsetting die employed to impart an edgewise bending pressure to the metal plate could not have a thickness greater than that of the metal plate. Consequently, in all previous attempts the thin blade of the offsetting die would buckle under the pressure imposed, and so fail to effect the offsetting operation. The difficulty previously encountered, however, has been overcome by the production of dies of peculiar form, and the pressure of which is directed angularly against the edges and sides of the metal plate, as disclosed in the said Patent No. 1,340,138, and Serial No. 367,799, the offsetting press being equipped with a pair of offsetting dies, each of which is provided with a curved portion designed to engage one of the edges of the plate and of a width approximating the thickness of the plate to be offset. Such dies are provided also with facing portions designed to bear on the sides of the metal plate and hold such plate against buckling as the dies are moved over each other to bring the edge engaging portions into contact with the plate and bend the latter as such edge engaging portions approach each other.

The foregoing statement of my invention pertains to the edgewise bending of rectangular plates of metal, in which the plane or side surfaces of the plate are prevented from distortion by reason of the angular pressure of the offsetting dies, the edge engaging portions of which are suitably contoured to bend the metal plate in the direction of its width and in the plane of the stroke of the dies. But in some types of automobile frame side

bars and cross bars it is very desirable to provide a reinforcement at points in the length thereof which are subject to unusual strains, with consequent liability to fracture. 5 In such cases it has been the practice to attach a separate reinforcing plate to the completed bar at the points which receive excessive strain. My invention enables me to produce an integral reinforcement of the 10 side or cross bar, and this I achieve by thickening or upsetting the plate at the desired points in the offsetting operation. Normally, the offsetting portions of the dies act only to produce a lateral displacement of 15 the longitudinal dimensions of the metal plate, such curved offsetting portions of the die moving in lines which maintain their parallelism, so that such offsetting portions of the dies are substantially equidistant at 20 all times in the offsetting operation. Under such conditions the metal of the plate can flow only from the edge of one offsetting die to the corresponding edge of the other. But when it is desired to thicken the plate at 25 certain points for the purpose of constituting the reinforcement described, the offsetting dies are formed and assembled so that at the points where reinforcement is desired, the dies will more closely approach each 30 other and thus narrow the plate at such points. To permit the metal of the plate at such times to flow in a direction which is transverse to the plane in which the plate lies, and so achieve the thickening desired, 35 I cut away the side surfaces of the offsetting dies in a slight degree, so that when the angular pressure of the offsetting dies is applied, the metal of the plate will also flow into the cut away portions of the dies, by 40 reason of the room for expansion thus provided, and in this manner the metal plate with thickened portions constituting the desired reinforcements is produced.

In the accompanying drawing,

45 Figure 1 is a plan view of a rectangular sheet metal plate showing the excess of width heretofore required to enable a curved blank of irregular outline to be punched therefrom, the view also showing in dotted lines the 50 outline of such curved blank, and the skeleton of the plate bordering on the curved blank indicating the amount or extent of the waste of material involved.

55 Fig. 2 is a plan view of a much narrower rectangular plate which is designed by my process to be bent in the direction of its width, so as to provide such plate with an irregular area and enable the curved blank indicated in Fig. 1 to be punched therefrom.

60 Fig. 3 is an edge view of the metal plate showing its normal construction.

Fig. 4 is a plan view of the metal plate shown in Fig. 2, and showing the configuration of the said plate produced by the edge-wise bending operation referred to, and

having indicated thereon by dotted lines the outline of the curved blank which may be punched therefrom, with the practical reduction of the waste material to a minimum.

Fig. 5 is a plan view of the curved blank 70 punched from the curved plate shown in Fig. 4.

Fig. 6 is an edge view of the blank shown in Fig. 5, but showing such blank as reinforced at its narrower or end portions, such 75 reinforcement following the thickening of the blank at such portions in the bending operation.

Fig. 7 is a perspective view of a curved flanged side bar for the frame of an automobile or other vehicle, and showing such 80 side bar as reinforced at its narrower or end portions.

Figs. 8, 9 and 10 respectively are views on the lines 8—8, 9—9, 10—10, Fig. 7, indicating by comparison the manner in which the 85 reinforcement described is created in the flanged side bar.

Fig. 11 is a rectangular plate from which a blank for a curved cross bar of an automobile frame may be produced.

Fig. 12 is a plan view of the plate shown in Fig. 11 after having been subjected to the edgewise bending operation.

Fig. 13 is a view in elevation of a curved flanged cross bar produced from the curved blank shown in Fig. 12 and reinforced through its central section.

Figs. 14 and 15 are sectional views on the lines 14—14 and 15—15, respectively, 100 Fig. 13, to show the reinforcement in the central portion of the cross bar.

Fig. 16 is designed to illustrate in a conventional manner the arrangement of the offsetting dies with a metal plate between 105 them, which plate will be bent edgewise to conform the edge lines thereof to the curvature of the dies, when the latter are caused to approach each other in the offsetting operation.

Fig. 17 is an end view, from the right, Fig. 16, showing the slight clearance provided in the dies to permit the expansion or thickening of the plate when the compressive strain is applied to the edges thereof.

Fig. 18 is a like view indicating the nature of the cross-sectional disturbance of the plate when compression is applied as described.

Fig. 19 is a diagrammatic view illustrating the movement of the rectangular plates into the offsetting press, and the movement of the curved blanks therefrom, after having been subjected to the offsetting operation, according to my improved process.

Referring to Figure 1 of the drawing, a rectangular plate of a width sufficient to enable a curved side bar blank of predetermined contour to be punched therefrom, is indicated by the numeral 10. This figure 130

has indicated thereon in dotted lines a curved flat blank 11, and by comparison of the respective outlines of the plate and the blank, it will be seen that the marginal or skeleton portion of the plate lying beyond the outlines of the blank embodies an area greatly in excess of that which is required in the formation of the blank. The excess of area residing in the marginal skeleton involves an appreciable amount of waste of expensive material, and the creation of such waste, due to quantity production, largely exceeds the legitimate manufacturing uses thereof, so that the waste must be disposed of as scrap, it having no other valuation.

Fig. 2 shows a rectangular plate 12 having a width which is approximately one third less than the width of the plate 10, and yet which plate 12 may be so transformed in the practice of my invention, that the facial extent of such plate will be changed so that the blank 11 may be punched therefrom, with a clear saving of at least a third of the material formerly required in producing the identical blank. The rectangular plate 12, after its transformation by edgewise bending, is indicated at 13 in Fig. 4, in which the dotted outlines of the blank 11 to be punched therefrom indicate by comparison the saving of material effected by the practice of my invention. Viewing Fig. 4, it will be seen that the skeleton of the plate lying outside of the lines indicating the blank, is so reduced that the waste resulting from the practice of the older processes is practically eliminated, and that the material constituting the said skeleton is of such small dimensions in all of its parts that it has no value for other manufacturing purposes. As a consequence, the waste material resulting from the practice of my invention is void of any value except that which merely attached to it as scrap.

As outlined in the statement of the invention at the commencement of this specification, it has been possible heretofore to impart a single curve or edgewise bend to a plural number of plates. But it has not been feasible to impart more than a single curve or edgewise bend to a plural number of plates in one operation, and such plural number of plates have of necessity been subjected to further bending operations when it was desired to produce additional curves or bends therein. Certain mechanical difficulties, hereinbefore referred to, have served to defeat all previous attempts to bend a single plate in the direction of its width. The difficulties referred to reside in the fact that it is not possible to construct a thin, flat offsetting die with strength sufficient to withstand the pressure applied to the edge of the plate in the bending operation, it being necessary that the plate to be bent be sustained by lateral guides to prevent

buckling of the plate, and the thin offsetting die being required to move into the space provided by the separation of the guides, and following the widthwise movement of the metal of the plate under the pressure exerted upon the offsetting die.

In my application filed September 12, 1921, Serial #500,019, I have disclosed the construction of the special dies which are employed to carry out my present invention, and will refer but briefly to such dies in the present case, such brief reference being sufficient for an understanding of the manner in which my present invention is put into practice. The offsetting dies which are used in carrying out my improved process of bending metal plates in the direction of their width, are conventionally shown in Figs. 16, 17 and 18. The lower die member 14 may here be described as constituted of a plate 85 having a flat face 15 upon which the metal plate 12 to be subjected to the bending operation is placed. At one edge the die member 14 is provided with an angularly formed offsetting die 16, which will be curved 90 throughout its length to produce the desired contour in the plate from which the blank is to be punched. The edge engaging portion 16 of the die will be commensurate with the gauge of the plate which it is desired to offset.

The companion offsetting die member 17, corresponding in construction to the offsetting die member 14 first described, is imposed upon the die member 14, so that the 100 flat faces 15 and 18 of the said dies bear upon the opposite sides of the plate 12, the offsetting edges 16 and 19 of the dies being at such times in line with the edges of the plate to be bent. The die member 14 is 105 maintained in a relatively fixed position, but an angular thrust is applied to the die member 17, as described in Patent No. 1,340,168, and application Serial No. 367,799, with the result that the flat faces of the dies engage 110 the sides of the metal plate 12 with a clamping pressure, which latter is sufficient to prevent the plate from buckling when the bending pressure is applied to the edges thereof, in the further movement of the die member 17, under the angular pressure described. The points and depressions of the correspondingly contoured edges 16 and 19 of the offsetting dies are opposite each other in the respective dies, so that the offsetting 115 pressure of the dies is applied to the opposite edges of the plate at points which are staggered with relation to each other. The points on the offsetting edges of the opposite dies are indicated at *x*, Fig. 16. The result of this arrangement and operation is that the metal of which the rectangular plate 12 is composed is caused to flow into the opposite depressions in the edge engaging portions of the dies, so that at the completion 120 125 130

of the stroke of the offsetting dies, the plate 12 will have its longitudinal lines distorted so as to conform to the contour of the offsetting portions of the dies, and a blank possessing the several curves desired will be produced in a single operation of the offsetting press. In the older practice, it was often necessary to cut transversely of the grain of the metal plate or strip to form the contoured blank, as shown in Fig. 1, but by the new method of edgewise bending the plate, the grain of the metal is made to lie parallel to the longitudinal dimensions of the curved blank, whereby the initial strength of the latter is preserved.

An offsetting press equipped with suitable dies, will constitute an element of the assemblage disclosed in my said Patent No. 1,397,020. The operation of such offsetting press will be in synchronism with the other elements constituting the assemblage referred to, the offsetting press performing its allotted work in a predetermined subdivision of the time-cycle in which the assemblage effects one complete movement. It is therefore necessary to the uninterrupted operation of the assemblage and the successful practice of my invention, when the offsetting press is operated as an element of the assemblage, that the rectangular metal plates be fed in regulated timing to the offsetting press in a continuous stream, the timed offsetting operation upon the rectangular plates being followed by a timed delivery of the curved plates for transmission by suitable conveyor mechanism to the next element of the assemblage designed for further operation upon the said plate. But when the offsetting press is operated independently of the assemblage, the time limitations may be removed.

The side margins of the blank are turned from the plane of the blank in the drawing operation, so as to form the flanges of the bar. Figs. 11 and 12 show the application of my improved process to the conversion of a rectangular plate 20 into a curved plate 21, from which a blank for a curved and flanged cross bar may be punched.

In automobile frames constructed from flanged metal plates, it happens that certain portions of the frame parts are subjected to severe strains, the construction being frequently weakened by the perforations in the frame parts through which pass the rivets employed for uniting the frame parts and some of the adjunctive devices and connections. Heretofore, it has been the practice to apply separate reinforcing plates to the parts of the frame at the points which are subjected to excessive strains, to overcome the inherent liability of the non-reinforced frame to fracture at the weakened points. The application of the reinforcing plates under the older method of

constructing automobile frames, involved additional expense for material, as well as for labor in producing and applying such reinforcements.

I propose to obviate the objections of the older practice, and produce in the parts of the automobile frame an integral reinforcement of the metal at the points which are subject to breaking strains. This result I achieve by thickening the cross sectional area of the plate from which the blank is punched, so that the side bar or other part will be sufficiently reinforced by the accretion of additional metal at the desired points.

To carry out this feature of my invention, I form the offsetting dies so that the side clamping faces therefore are separated in an increased degree in certain sections, so as to provide room for expansion of the metal in a plane transverse to that in which the plate lies. At those points in the length of the side bar where the reinforcement is desired, the edgewise bending portions of the offsetting dies will compress the metal of the plate 12 in the offsetting operation, and at the same time the metal of the plate will flow laterally from the direction of its movement in the bending operation, and completely fill the slight clearance provided in the cut out portions in the face of the dies. Fig. 17 indicates the normal thickness of the plate 12, and Fig. 18 indicates the same plate after action thereon by the offsetting dies, which in their relative approach act to compress the metal of the plate 12 in the desired sections, and cause the metal of the said plate 12 to flow in a plane transverse to its width, during the bending operation.

Fig. 6 shows an edge view of a curved side bar blank 13, the ends 22 and 23 of which are shown as having been gradually thickened from the normal gauge of the plate, so as to constitute the plate 13 with integral reinforcements at the sections desired.

Fig. 7 is a perspective view of a side bar of an automobile frame, the ends 24 and 25 of such side bar being integrally reinforced in the manner described, so that the side bar will sustain the strains imposed thereon, notwithstanding the fact that the metal has been weakened by perforations for the attachment of the adjunctive devices. Fig. 9 is a cross sectional view showing the normal gauge of the stock from which the side bar is formed, and Figs. 8 and 10 show by comparison the integral reinforcement, produced as described.

Fig. 13 shows one form of a curved cross bar 26, the arch of which is ordinarily required to be thin in order to provide a clearance for the shaft of the car. Fig. 15 shows the normal gauge of the metal plate from which the cross bar is formed, and Fig. 14 shows in cross section the manner of inte-

grally reinforcing the arch of the cross bar by thickening the plate in order to overcome the weakness inherent in a cross bar not reinforced at its central point, which, in the 5 construction illustrated, is the seat of its greatest weakness.

In certain classes of work, the edgewise bending operation may be performed upon blanks of simple outline, and which need 10 only to be curved to adapt them to their intended use. The intermediate step of blanking is not, therefore, an essential element of my new process, by which curved flanged bars are produced from rectangular metal 15 plates which are bent in the direction of their width, and which in a single bending operation have all of the necessary curves imparted thereto.

In an application filed by me on September 20, 1921, Serial No. 500,018, as a division in part of this case, I have claimed the product resulting from the practice of the invention herein disclosed.

Having thus described my invention, what 25 I claim and desire to secure by Letters Patent of the United States, is:

1. The process of producing curved, flanged bars, which consists in confining a single wide metal plate by pressure upon the sides 30 thereof, subjecting the plate to bending pressure applied to the edges thereof at separated points along the opposite edges of the blank, such separated points at one edge of the plate being staggered with relation to the 35 points on the opposite edge, whereby the metal of the plate will be caused to flow away from the longitudinal center line of the plate, punching a curved blank from the plate, and turning the curved side margins of the blank from the plane thereof to form the flanges.

2. The process of making a curved, flanged bar, which consists in confining a single wide metal plate by pressure upon the sides thereof, bending the said plate in the direction of its width by pressure applied at separated points to the opposite edges thereof, such 45 separated points being staggered with relation to the opposite edges of the plate, to distort the edge lines of such plate, cutting a curved blank from the plate, and turning the side margins of the blank from the plane thereof to form the flanges of the bar.

3. The process of making a curved, flanged bar, which consists in clamping a single wide metal plate against disturbance of the side planes thereof, bending the said plate in the direction of its width by pressure applied to the edges and at separated points staggered with relation to each other upon the opposite 50 edges of the plate, to distort the edge lines of such plate, and turning the margins away from the plane of the plate to form the flanges of the bar.

4. The process of making a curved, flat

plate, which consists in clamping a single wide metal plate against disturbance of the side planes thereof, and bending the said plate in the direction of its width by pressure applied at points alternating on the opposite 70 edges thereof, to cause the metal of the plate to flow away from the longitudinal center line of the plate.

5. The process of converting a rectangular plate into a curved, flanged bar, integrally reinforced in sections of its length, which consists in clamping the plate to preserve the side planes thereof and prevent buckling, bending the plate in the direction of its width by pressure applied at points alternating on the opposite edges thereof and thickening the plate in sections thereof by compression in the bending operation, and turning the side margins of the plate from the plane thereof to form the flanges of the 85 bar.

6. The process of converting a rectangular plate into a curved, flanged bar, integrally reinforced in sections of its length, which consists in clamping sections of the plate to 90 preserve the side planes thereof, bending the plate in the direction of its width by pressure applied at points alternating on the opposite edges thereof and thickening the plate in the unclamped sections thereof by compression of the unclamped portions in the bending operation, cutting a blank from the said curved plate, and turning the side margins of the plate from the plane thereof to 95 form the flanges of the bar.

7. The process of converting rectangular metal plates into curved plates for the manufacture of automobile frame bars, which consists in feeding such rectangular plates in 100 single succession to bending dies, clamping the plate to prevent distortion of the side planes thereof, applying a bending pressure to the edges of the plate at separate points alternating on the opposite edges thereof 105 while the sides are clamped, to cause the metal of the plate to flow away from the longitudinal center line of the plate, thickening the plate in sections by compression and withdrawing the curved plates from the bending dies in the order in which they are 110 fed to the dies.

8. The process of making curved flat blanks, which consists in clamping a single, wide metal plate against disturbance of the side planes thereof, bending the said plate in the direction of its width by pressure applied to the opposite edges thereof at points which are staggered with relation to each other, and cutting a curved blank from the 115 bent plate.

9. The process of making curved flat blanks which consists in simultaneously applying clamping pressure to the sides of a single, wide metal plate and bending pressure to the edges thereof, such bending pres- 120

sure being applied at points which are staggered with relation to each other on the opposite edges of the plate, and cutting a blank of curved outline from the said bent plate.

5. 10. The process of converting flat plates into plates of curved form, which consists in confining a single wide metal plate by pressure upon its sides to prevent buckling and simultaneously therewith applying bending

pressure to the opposite edges thereof. 10

In testimony whereof, I have signed my name at Milwaukee, this 29th day of March, 1920.

R. STANLEY SMITH.
